UNITED STATES PATENT OFFICE.

GEORGE BLANCHARD, OF NEW YORK, N. Y.

LAMP.

Specification of Letters Patent No. 29,456, dated August 7, 1860.

To all whom it may concern:

Be it known that I, GEORGE BLANCHARD, of the city, county, and State of New York, have invented a new and Improved Mode of 5 Converting a Lamp into a Lantern; and I do hereby declare that the following is a full and exact description thereof.

The nature of my invention consists in the lantern jacket B, in combination with the 10 lamp A and handle C on the lantern jacket B, so when the handle C is taken hold of the lamp A drops down, the whole forming a lantern, as will be seen in the accompanying drawing.

15 To enable others skilled in the art to use and make my invention, I will proceed to describe its construction and operation.

I construct my lamps in tubular or oblong form, with a piece of perforated tubing

B on the outside, this having a piece of wire 20 fastened on the bottom, taking effect upon the seam on the top of the lamp A to prevent the lamp from dropping out. A ring or handle C is soldered on the perforated tube B so that when taken hold of, it becomes ex- 25 tended by its own weight.

What I claim as my invention and desire to secure by Letters Patent is—

The combination of the lamp A with the slide or tube B when the same is provided 30 with the handle C, so that when taken hold of the lamp drops down by its own weight, thus affording a lantern.

GEORGE BLANCHARD.
